UNITED STATES PATENT OFFICE

2,562,701

GRAVITATIONAL MOTION FOR VERTICAL
LEVERS ON TWO-WHEELED LOAD TRANS-
PORTING VEHICLES

Peter Danalis, Rockaway Beach, N. Y.

Application April 21, 1948, Serial No. 22,354

1 Claim. (Cl. 280—53)

1 This invention relates to new and useful improvements in two-wheeled load-transporting vehicles, and, more specifically, there is provided by the invention a carriage supported on and rotatively mounting a pair of spaced side wheels, with said carriage incorporating a structure for swingably mounting a weight, as a load-carrying body, in such manner that, although when the vehicle is stationary such weight is so disposed relative to the axis of rotation of the wheels that its center of gravity is vertically below their axis of rotation, incidental to putting the vehicle in motion said weight is swung to assume and maintain a position so related to said axis that the pulling or pushing force employed to effect motion of the vehicle is markedly reduced.

For achieving this result, as in a trundle cart or one to be pulled or pushed by a person handling the same, the invention is preferably carried out by providing a carriage including an inverted yoke, by providing an arm normally vertically upstanding from the yoke structure, by providing a pull or push rod having its end adjacent to the carriage pivotally connected to the upper end of said arm, by mounting the wheels on opposite sides of the yoke structure and at points intermediate the tops and bottoms of the two depending side limbs of the yoke structure, and by pivotally mounting the load-carrying body within the yoke structure at points at or near the bottoms of said side limbs.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

Fig. 1 is an end elevation of an embodiment of the invention as now favored.

Fig. 2 is a side elevation thereof, showing in dot and dash lines redispositions of certain of the parts during movement of the vehicle in response to a pulling or pushing force applied thereto.

Fig. 3 is a side elevational view of the yoke structure per se with a portion of the arm extending therefrom.

Fig. 4 is an enlarged partial vertical sectional view taken on the line 4—4 of Fig. 2.

Referring to the drawing in detail, the carriage aforesaid is illustrated as comprising a yoke structure 10 of inverted U type, carrying intermediate the tops and bottoms of its two depending side arms 11 journaling means, as indicated

at 12, for the two wheels 14, with each such when carrying its own stub-axle 15.

At or near the lower ends of the arms 11 of the yoke structure 10, and between said limbs, the element 16 is rotatively suspended, as by way of the trunnion means indicated at 17. This element 16, theoretically a weight to be transported, for practical purposes would be a hollow body, including, according to the shape shown, a bottom wall, front and side walls and two end walls, and so providing a chamber therein for receiving a load to be transported.

From Fig. 3 it will be noted that the bottom ends 11a of the side arms 11 of the yoke structure 10 are offset from the journaling means 12 to the free bottom ends of the side arms 11. It is the offset ends 11a of the side arms 11 which are formed with openings 17a for the trunnion means 17 of the element 16. As shown in Fig. 3, the journaling means 12 and the openings 17a will be disposed to one side of the journaling means 12.

Suitably rigidly secured to the top of the yoke structure 10, as at 19, is an arm 20 which, relative to the element 16, constitutes in effect a lever of the first class, with its fulcrum at the journaling means 12. As here shown, the arm 20 is of rather considerable length, and therefore the lever is one of high mechanical advantage.

The weight of the element 16 tends to retain the yoke structure 10 in a position in which the trunnion means 17 will be vertically below the journaling means 12 so that the arm 20 will extend upwards at an inclination from the vertical, as shown in full lines in Fig. 2. This is caused by the offset formation of the lower ends 11a of the side arms 11 of the yoke structure 10.

A pulling or pushing handle 21 is provided, and is connected at one end to the upper end of the arm 20. The handle 21 may have a hand-grip 22 secured to its end remote from the arm. The coupling between the handle 21 and the arm 20 is shown as in the form of a universal joint incorporating a collar 22' fixed to the handle 21 and having suitably rotatively and non-withdrawable mounted therein a fork 23 pivotally connected at 24 to a ring 25 loosely sleeving a reduced cylindrical portion 26 at the upper end of the arm 20 and there retained by a washer 27 held by a screw 28.

Normally, that is, with the vehicle stationary, the parts are disposed as shown in full lines in Fig. 2. Then, with the center of gravity of the load at the bulk center of the element 16, the axis 55 of the journaling means 12 will be vertically

above the axis of the trunnion means 17, the arm 20 will be inclined vertically from the top of the yoke structure 10, while the weight represented by the element 16 and its load if any will have the center of gravity thereof vertically below said axis.

When the arm 20 is moved to extend vertically from the yoke structure 10, as indicated by the dot and dash lines 26^a in Fig. 2, the offset ends 11^a of the side arms 11 of the yoke structure will move in the opposite direction to move the trunnion means 17 to one side of the journaling means 12, shifting the element 16 to the position illustrated by the dot and dash lines 16^a in Fig. 2, so as to shift the center of gravity of the element 16 to one side of the journaling means 12.

However, preparatory to applying a pulling or pushing force to the vehicle by way of the arm 20, this arm must be lowered to a convenient inclination, correspondingly raising the element 16 to one side of the journaling means 12, such that its center of gravity is displaced from its normal vertical alignment with the axes of the journaling means 12 and the trunnion means 17, with the result that the pulling or pushing force required to move the vehicle is correspondingly reduced. While the weight represented by the element 16 must of course be preliminarily raised, the effort needed for this is very slight, in view of the functioning of the arm 20 as a lever of the first class having its fulcrum several times closer to the weight than to the point of application of the force at the free end of the arm.

When the vehicle is to be moved by pulling it, as by use of the hand-grip 22, and with the arm 20 lowered and the handle 21 extended axially therefrom, the preliminary rocking of the arm 20 out of the vertical is effected by a pull on the handle 21 while the latter is extended following initial swinging out of the handle.

When the vehicle is to be moved by pushing it, preliminary rocking of the arm 20 out of the vertical may be effected as above by first swinging the handle 21 outward and then pulling down on the hand-grip 22 until the upper end of the arm 20 is lowered sufficiently for easy manual engagement with said end for then applying a pushing force thereto. The handle 21 may be used for pushing the vehicle, particularly when, in lieu of a universal joint as above described between the arm 20 and the handle, the arm and handle are connected by a coupling means comprising a pivotal connection incorporating merely a single horizontal axis.

The pivotal mounting of the element 16 below the rotation axis of the wheels 14 is particularly useful in reducing the pull required to cause the wheels 14 to roll over bumps in the road. Let us assume, that the arm 20 is extended forwardly of the device and that the same is being pulled in a forward direction. This forward extension of the arm 20 causes the offset ends 11^a of the arms 11 of the yoke structure 10 to be extended behind the turning axis of the wheels 14 which also places the center of gravity of the element

16 and articles contained therein behind the turning axis of the wheels 14. This causes the center of the pull of gravity to be behind the point of contact of the wheels 14 with the ground over which they are rolling. Therefore, if a bump in the road is encountered by one of the wheels 14 or simultaneously by both of the wheels, less pull will be required to roll the wheels onto and over the bump and/or bumps, as the wheels will be fully over the bump before the center of gravity of the element 16 passes directly over the bump and/or bumps.

The universal joint between the adjacent ends of the arm 20 and the handle 21 permits movement of the handle 21 in all directions relative to the end of the arm 20 for shortening the pulling tongue as may be required to facilitate movement of the vehicle in close quarters.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new and desire to secure by United States Letters Patent is:

In an article of the class described having a yoke of inverted U-shape with a top arm and spaced depending side arms to the outer faces of which wheels are rotatively mounted closely adjacent the bottom ends thereof and a load between the side arms and pivotally mounted on the bottom ends thereof, an arm of considerable length fixedly secured at one end to the top arm to extend upward from the yoke, a handle extended along the front of said arm, a hand-grip mounted on the bottom end of said handle, a collar fixed to the top end of said handle, said arm being formed at its top end with a reduced cylindrical portion, a ring turnably sleeving said cylindrical portion, a washer secured to the outer end of said cylindrical portion retaining said ring in position on said cylindrical portion, trunnions extended laterally from opposite sides of said ring, and a fork fixedly connected to said collar and having spaced tines extended along opposite side of said ring and pivotally connected to said trunnions.

PETER DANALIS.
